SHEET FEEDING AND TURNING APPARATUS

Lincoln A. Cundall and William H. Blaisdell, Rochester, N.Y., assignors to Eastman Kodak Company, Rochester, N.Y., a corporation of New Jersey

Application October 15, 1956, Serial No. 616,009

3 Claims. (Cl. 271—65)

This invention relates to sheet feeding apparatus, and particularly to an apparatus for feeding sheets individually along a given path to a discharge point where they are stacked and including means for automatically turning over each sheet as it reaches the discharge point in order to cause the natural curl of the sheets to be overcome by the weight of the sheets in the stack.

This invention is an improvement over the sheet feeding and turning apparatus disclosed in U.S. Patent 2,649,303, which issued August 18, 1953.

In certain enterprises using individual cut sheets of paper or other flexible material, it is essential that the sheets be flat rather than curled. One enterprise in which curled sheets are particularly troublesome is the photographic finishing business where cut sheets of film and light-sensitive paper are used and must generally be held flat in a focal plane for exposure and should be flat to facilitate certain processing procedures to which the sheets are subjected. Cut sheets out of photographic materials are particularly subject to curling tendencies because they are coated on one side with light-sensitive coatings which have different stretch or shrinkage characteristics than the base of the sheet.

The above-noted patent discloses an apparatus for turning over alternate sheets in the packaging of photographic material so that the curling tendency of adjacent sheets will offset each other. This patented structure, however, is somewhat complicated by reason of the fact that the sheet turning mechanism is selective in operation and thus requires a synchronizing system between the cut sheets and the turnover roll and stacking mechanism which is sometimes difficult to keep in proper working order, particularly when operating at high speeds.

The primary object of the present invention is to provide an improved apparatus for feeding individual cut sheets to a stacking point and which includes means for automatically turning over every sheet as it approaches the stacking position.

Another object is to provide a sheet feeding apparatus of the type described in which the sheet turning mechanism is continually operated along with the sheet feeding mechanism and requires no synchronization between the cut sheets and turnover roll stacking mechanism.

And a further object is to provide an improved sheet turnover mechanism which is relatively simple both in construction and operation so that it can be constructed rather inexpensively and will operate satisfactorily at high speeds with the minimum of supervision.

The novel features that we consider characteristic of our invention are set forth with particularity in the appended claims. The invention itself, however, both as to its organization and its methods of operation, together with additional objects and advantages thereof, will best be understood from the following description when read in connection with the accompanying drawings, in which:

Fig. 1 is a side elevation of a sheet feeding and stack-

2

ing apparatus constructed in accordance with a preferred embodiment of the present invention and having a portion of the side supporting frames broken away so as to show the parts of the feeding apparatus and their drives in full lines instead of dotted lines;

Fig. 2 is an end sectional view of the feeding and stacking apparatus shown in Fig. 1 and taken substantially on line 2—2 of Fig. 1;

Fig. 3 is an enlarged elevational view of one of the turnover rolls and showing how the rolls pick up the leading edge of a sheet advanced to the discharge point of the apparatus to turn the sheet over and deposit it in the stack;

Fig. 4 is an enlarged vertical sectional view of one of the sheet turnover rolls; and

Fig. 5 is a schematic view showing a sheet in the process of being turned over by the mechanism and showing a previously turned over sheet just falling into the stack of sheets.

Referring now to the drawings wherein a preferred embodiment of the present invention is shown, the sheet feeding and turning apparatus is supported by a framework comprising a horizontal base 10 from which a pair of vertical side frames 11 extend in spaced parallel relation to serve both as supports for the sheet conveying mechanism and its drives as well as serving as covers for this apparatus. The sheets S of flexible material, such as paper, to be handled by this apparatus are moved along by a plurality of narrow endless horizontal conveyor belts 12 supported on rolls 13 fixed to shafts 14 extending between the side frames 11. One of the shafts 14 is driven by a chain 15 engaging a sprocket 16 on the end of one of the shafts 14 and a sprocket 17 on the end of another shaft 18 extending between the side frames 11 in parallel relation to the shafts 14. This latter shaft 18, in turn, is driven through a chain or belt 19 and sprockets 7 and 8, sprocket 7 being fixed to shaft 35 extending between the side frames 11 and being continuously driven by a motor M through chain or belt 40 36 engaging a sprocket 84 fixed to shaft 35, see Figs. 1 and 2. Although, as shown, the sheet conveyor is made up of 12 narrow belts, see Fig. 2, it will be understood that a fewer number of belts, even a single belt, could be used. The sheets S come from any source, the only requirement being that they be placed on belts 12 flatwise and in spaced relation. One representative source of such sheets might be a chopper which intermittently chops a continuous web of paper into sheets of a given length and drops the sheets directly on the belts 12 or onto another conveyor which feeds them onto belts 12. In Fig. 1, we have shown the feeding apparatus associated with such a belt B which feeds the sheets from a chopper to the belts 12.

The sheets S are held flat on the lower conveyor belts 12 by means of upper conveyor belts 20 corresponding in number to belts 12 and carried on rolls 21 mounted on shafts 22 extending between the side frames in parallel relation to the shafts 14. The lower reach of the upper conveyor belts may directly contact the upper reach of the lower conveyor belts to be driven by frictional contact if the rolls 21 are fixed to shaft 22 and said shaft is mounted in bearings for free rotation as indicated. On the other hand, the rolls 22 may have their own drive, if desired, in which case the speed of movement of the two belts (12 and 20) should be the same. These conveyor belts feed the sheets S to a discharge point where they are deposited in a stack indicated at 23 on a suitable pallet 24 supported by a shelf 25 carried by pillars 26.

If only the conveyor belts were used, the sheets S would all be discharged onto the stack with the same side up as was up during movement to the stack. In or-

der to present a package of flat sheets, the apparatus is provided with means for automatically turning every sheet as it is deposited on the stack so that the curling tendencies which the sheets might possess will tend to counteract one another. In this connection, if these sheets are photographic material coated with a light-sensitive emulsion, then the emulsion side of the sheets S is facing upwardly as they move through the belt conveyors and if such sheets were stacked without turning, the normal tendency for such emulsion-coated sheets to curl in the direction of the emulsion side would result in all of the sheets in the stack curling upwardly. By turning each of the sheets over at the time they are placed in stacked relation, the curling tendency of the sheets is opposed by the weight of the stack and the sheets are thus flattened.

Coming now to the present invention, we have provided a sheet-turning mechanism which is much simpler in both construction and operation than the sheet-turning mechanism used in above-noted Patent 2,649,303. This sheet-turning mechanism comprises a plurality of turnover rolls 30 , in this case eleven, which are each fixedly mounted on a shaft 31 extending between the side frames 11 in parallel relation with the shaft 18 and located adjacent the discharge point of the sheet conveying system. As clearly shown in Fig. 2, these sheet turnover rolls 30 are spaced along the shaft 31 so that one of them is positioned between each adjacent pair of conveyor belts 12 . As most clearly shown in Figs. 3 and 4, each turnover roll 30 comprises a pair of flanges 32 connected near their circumference by an annular web 33 . A plurality of sheet-engaging members 34 in the form of fingers or U-shaped bales, see Fig. 4, are pivotally mounted in circumferentially spaced relationship about the periphery of the turnover roll to move between an operative position wherein they extend transversely of, and in an inclined relation toward, the path of the sheets and an inoperative position where they lie substantially tangentially to the periphery of the roll, see the dotted line position in Fig. 3. The sheets S are fed tangentially into the turnover rolls by the conveyor belts 12 and the rolls are driven at a slower speed than the conveyor belts so that the leading edge of a sheet will be confined by one of the sheet-engaging fingers 34 before the sheet starts to turn over. The sheet-engaging members 34 may be formed from wire so as to be very light and rigid and they are normally held in an upright or operative position by small permanent magnets 35 which attract the turned-down arm 36 on each sheet-engaging member and act as a stop therefor as well as serving to hold the sheet-engaging fingers in operative position through magnetic attraction.

The sheet turnover rolls 30 are continually driven in the same direction as the sheets by means of a chain or belt 37 engaging sprockets or pulleys 38 and 39 on shafts 31 and 35 , respectively. The diameters of the sprockets or pulleys 38 and 39 are such that the sheet turnover rolls 30 are driven at a slightly slower linear speed than the linear speed of the conveyor belts 12 which feed the sheets to the discharge point. By virtue of this difference in linear speed, the conveyor belts 12 tend to force the leading edge of a sheet S against one of the sheet-engaging members 34 carried by the turnover rolls so that the leading edge of the sheet is positively confined by one of these sheet-engaging members and the leading edge of the sheet is carried around the turnover rolls in wrapped relation therewith, see Figs. 1 and 5. As the leading edge of a sheet is being wrapped around the turnover rolls and thereby directed away from the normal path of the sheets, the trailing edge of the engaged sheet is being fed at a faster rate than the leading edge so that the effect is for the trailing edge of the sheet to balloon out, as shown clearly in Figs. 1 and 2, and turn the sheet over as it is laid in the stack 23 . As clearly shown in Figs. 1 and 5, those sheet-engaging members behind the one engaged by the leading edge of the sheet are readily pivoted to their

inoperative position as the sheet wraps around the turnover roll, since the magnetic force between the arm 36 of each sheet-engaging member 34 and its corresponding magnet 35 is sufficient to merely hold these members in an operative position but not sufficient to oppose pivotal movement of the members to their inoperative position as a sheet is wrapped around the turnover roll. When a turnover roll is provided with as many sheet-engaging fingers as we have shown in Fig. 3, it has been found necessary or desirable from the structural standpoint to mount the magnets 35 for every other sheet-engaging finger on one side of the roll and the remaining magnets for the other fingers on the opposite side of the roll as shown. This necessarily involves reversing the side of the sheet engaging fingers at which the down-turned arm 36 thereof, which is adapted to engage the magnet, is located.

The rotating turnover rolls 30 turn over the leading edge of the sheet until the leading edge hits the knock-out fingers 40 fixed to and extending vertically from the pallet 24 and situated intermediate the turnover rolls. When the leading edge of the sheet strikes these knock-out fingers, they are disengaged from the sheet-engaging fingers of the turnover rolls and the sheets are free to fall into the stack 23 on the pallet 24 in turned-over relation. After a sheet is knocked out of disengagement with one of the members 34 , the other members 34 which were normally moved into and held in their inoperative position by the sheet reset themselves at the knock-out stops 40 by reason of the weight of the fingers causing them to fall against the permanent magnets 35 which lock them in operative position.

It will thus be seen that with this sheet turnover mechanism there is no synchronization problem since the turnover roll is continually rotating at all times. It is only necessary that the linear speed of the turnover roll be somewhat less than the linear speed of the sheet conveyor system in order that the leading edge of a sheet will be engaged and confined by one of the sheet-engaging members on the turnover roll so as to direct it away from the path of the sheets and cause the desired turnover of the sheets. Depending upon the number of sheet-engaging fingers carried by the turnover roll, the separation between the sheets carried by the conveyor system to the turnover roll may vary from close to wide apart. By virtue of the manner in which the sheet-engaging fingers are mounted on the turnover roll, they are always in their operative position when they move into the path of the sheets being forwarded by the conveyor belts and if the sheet-engaging fingers are of sufficient number to give a slight separation, then there will be a finger present to engage the leading edge of a conveyed sheet regardless of the closeness with which the sheets might be being carried forward by the conveying system. With this arrangement the emulsion side of the sheet is up and since this top surface is never engaged by the fingers of the turnover rolls, the coating is not subjected to abrasion by the turnover mechanism nor is it necessary to slide one sheet on the other during stacking and thereby cause abrasion to the coating on the sheets.

While we have shown and described certain specific embodiments of the invention, we are fully aware that many modifications thereof are possible. Our invention, therefore, is not to be limited to the precise details of construction shown and described, but is intended to cover all modifications coming within the scope of the appended claims.

Having thus described our invention, what we claim as new and desire to secure by Letters Patent of the United States is:

1. In a sheet feeding and turning mechanism the combination with a means for conveying individual flexible sheets separately and in a flatwise condition along a given path at a given rate to a discharge point; a sheet turning roll mounted at said discharge point on an axis

extending transversely to said path and located at a point below said path so that the periphery thereof lies adjacent but below said path; a plurality of sheet-engaging members pivotally mounted on said roll in spaced relation circumferentially thereof to move between an operative position, wherein a portion of each thereof extends from the periphery of said roll across and at an angle to the path of sheets reaching said discharge point to engage and confine the leading edge of a sheet as it reaches said discharge point, and an inoperative position, wherein said portion lies substantially tangent to the periphery of said roll to permit a sheet to be wrapped around the periphery of said roll; means normally holding said sheet-engaging members in their operative position and permitting them to be moved to their inoperative position by a sheet as it wraps around said roll; means for continually rotating said roll in the same direction as, but at a slower linear speed than, said conveying means whereby the leading edge of a sheet as it reaches the discharge point is engaged and confined by one of said sheet-engaging members and carried away from said path while the trailing edge of the sheet is continually fed along said path at a faster rate to cause the sheet to turn over, and means for engaging the leading edge of said sheet to disengage it from said sheet-engaging member when the leading edge is displaced sufficiently from said path to cause the sheet to be turned over as the result of the continued feeding of the trailing edge along said path.

2. In a sheet feeding and turning mechanism the combination with a means for conveying individual flexible sheets separately and in a flatwise condition along a given path at a given rate to a discharge point; a sheet turning roll mounted at said discharge point on an axis extending transversely of said path and located at a point below said path so that the periphery thereof lies adjacent but below said path; a plurality of sheet-engaging members pivotally mounted on said roll in spaced relation circumferentially thereof to move between an operative position, wherein a portion of each thereof extends from the periphery of said roll across and at an angle to the path of sheets reaching said discharge point to engage and confine the leading edge of a sheet as it reaches said discharge point, and an inoperative position, wherein said portion lies substantially tangent to the periphery of said roll to permit a sheet to be wrapped around the periphery of said roll; means normally holding said sheet-engaging members in their operative position and permitting them to be moved to their inoperative position by a sheet as it wraps around said roll, and including a magnet carried by the roll, and each sheet-engaging member having a metal arm which constitutes an armature adapted to be attracted by said magnet; means for continually rotating said roll in the same direction as, but at a slower linear speed than, said conveying means whereby the leading edge of a sheet as it reaches the discharge point is en-

gaged and confined by one of said sheet-engaging members and carried away from said path while the trailing edge of the sheet is continually fed along said path at a faster rate to cause the sheet to turn over; and means for engaging the leading edge of said sheet to disengage it from said sheet-engaging member when the leading edge is displaced sufficiently from said path to cause the sheet to be turned over as the result of the continued feeding of the trailing edge along said path.

5 3. In a sheet feeding and turning mechanism the combination with a means for conveying individual flexible sheets separately and in a flatwise condition along a given path at a given rate to a discharge point; a sheet turning roll mounted at said discharge point on an axis extending transversely of said path and located at a point below said path so that the periphery thereof lies adjacent but below said path; a plurality of sheet-engaging members pivotally mounted on said roll in spaced relation circumferentially thereof to move between an operative position, wherein a portion of each thereof extends from the periphery of said roll across and at an angle to the path of sheets reaching said discharge point to engage and confine the leading edge of a sheet as it reaches said discharge point, and an inoperative position, wherein said portion lies substantially tangent to the periphery of said roll to permit a sheet to be wrapped around the periphery of said roll; said sheet-engaging members being pivoted on said roll so as to be normally moved toward their operative positions by gravity during rotation of the roll; means normally holding said sheet-engaging members in their operative position and permitting them to be moved to their inoperative position by a sheet as it wraps around said roll, and including a plurality of permanent magnets carried by said roll and each sheet-engaging member having a metal arm which constitutes an armature adapted to be attracted by one of said magnets; means for continually rotating said roll in the same direction as, but at a slower linear speed than, said conveying means whereby the leading edge of a sheet as it reaches the discharge point is engaged and confined by one of said sheet-engaging members and carried from said path while the trailing edge of the sheet is continually fed along said path at a faster rate to cause the sheet to turn over; and means for engaging the leading edge of said sheet to disengage it from said sheet-engaging member when the leading edge is displaced sufficiently from said path to cause the sheet to be turned over as the result of the continued feeding of the trailing edge along said path.
